UNITED STATES PATENT OFFICE

FREDERICK W. BERNAU, OF HILLSIDE, NEW JERSEY, ASSIGNOR TO ELLIS ADDING TYPEWRITER COMPANY, OF NEWARK, NEW JERSEY, A CORPORATION OF NEW JERSEY

OVERDRAFT NUMERAL KEY LOCKING MECHANISM

Application filed September 13, 1926. Serial No. 135,141.

This invention relates to an overdraft numeral key locking mechanism for calculating machines.

In my Patent 1,508,267 September 9, 1924, 5 there is set forth a total and subtotal key locking mechanism which is automatically operated when an "overdraft" occurs in the accumulator, and in my Patent No. 1,731,701 dated October 15, 1929 disclosure is made 10 of locking means for the starting bar or operating means of the machine.

The present invention has for its object 15 the provision of improved means, operated automatically when an overdraft condition exists in the accumulator of a calculating machine thereupon to lock the undepressed numeral keys and to lock the previously depressed keys which have caused the overdraft so that release of said keys cannot be 20 had until the operator releases the locking means.

My numeral key locking mechanism may 25 be used in conjunction with the total and subtotal key overdraft locking mechanism of my Patent No. 1,508,267, or, the starting bar overdraft locking mechanism of my Patent No. 1,731,701, or, in connection with both of said mechanisms, or, it may be used on a calculating machine where neither of said 30 locking mechanisms are present.

When referring to a "calculating" machine, it is to be understood that I have reference to an adding, or subtracting or listing machine of any character because, while the 35 present improvements have been devised particularly for use in connection with the "Ellis" printing calculating machine as set forth in the patents to Halcolm Ellis, No. 1,197,276 September 5, 1916 and No. 1,203,863 November 7, 1916, and other patents disclosing the Ellis type of machine, nevertheless my improvements may be adapted to other calculating machines without departing from the principles of the invention.

In a calculating machine provided with 45 my improvements, the operator may continue to use the keyboard until an overdraft or negative amount is represented on the accumulator. When an overdraft condition occurs, the mechanism is automatically oper-

ated by the accumulator to lock the numeral keys of the keyboard and when an attempt is made thereafter to depress the raised numeral keys for the purpose of further addition or subtraction, the locked condition of 55 said keys constitutes a signal, notifying the operator of the overdraft condition.

It then becomes necessary for the operator to release the locking means which have rendered the numeral keys inoperative. This 60 can be accomplished by depressing the adding key, and starting bar and causing the machine to go through its cycle of operations, thereby adding back into the credit accumulator the amount represented by the 65 locked depressed keys constituting the overdraft.

My improvements are illustrated in connection with so much of the "Ellis" machine as will afford a clear understanding of the 70 construction and mode of operation thereof, but reference is to be had to the Ellis Patents Nos. 1,197,276, and 1,203,863, and to my Patent 1,508,267 for illustration of those mechanisms which, having now become well- 75 known to the art, require no detail illustration herein.

In the accompanying drawings:

Figure 1, is a detail rear elevation, the operating shaft being in normal position;

Fig. 2, is a similar view, the shaft having been turned;

Fig. 3, is a section on line 3-3, Fig. 1;

Fig. 4, is a section on line 4-4, Fig. 2;

Fig. 5, comprises detail views of the lever 85 and safety pawl;

Fig. 6, comprises detail views of the locking trigger;

Fig. 7, is a view like Fig. 1, the keys and 90 their latches being omitted;

Fig. 8, is a view like Fig. 2, but with certain parts omitted, the locking trigger being arranged to block the controlling bar, as when an overdraft exists;

Fig. 9, is a view like Fig. 7, the operating shaft having returned to normal position but the locking trigger remaining in position to prevent restoration of the controlling bar;

Fig. 10, is a detail view showing the locking 100

trigger in normal position, as when no overdraft exists in the machine;

Fig. 10, is a similar view, illustrating how the locking trigger is operated to prevent restoration of the controlling bar when an overdraft occurs.

Figs. 11 and 12 are, respectively, front and rear elevations of the keyboard section of the machine of the Ellis Patent No. 1,197,276 showing how my improvements co-operate therewith;

Fig. 13 is a side elevation of the numeral key latch and lock and the rack lock thereof;

Fig. 14 is a vertical center section of the adding and subtracting machine of the Ellis Patent 1,203,863, the parts being in normal position;

Fig. 15 is a detail elevation of the numeral key release mechanism thereof, the parts being normal for adding;

Fig. 16 is a detail view showing the means by which the numeral key release bar is operated;

Fig. 17 is an elevation of the left hand side of the Ellis machine as disclosed in the Bernau Patent No. 1,508,267, showing the subtracting key in depressed position, the mechanism for controlling the adding and subtracting accumulator, and the overdraft locks for the total and subtracting keys, the latter being in normal position;

Fig. 18 is a perspective skeleton view of the Ellis machine as illustrated in the Bernau Patent No. 1,508,267 the side frames being in dotted lines, showing the overdraft mechanism and operative connections to the locks for the total and sub-total keys, and the decimal slide, the parts being in normal position;

Fig. 19 is a partly sectional, partly elevational, detail view of the overdraft mechanism as set for carrying on a subtracting operation, before an overdraft has taken place; and

Fig. 20 is a similar view showing the positions of the parts after an overdraft has taken place.

Reference is to be had more particularly to Figs. 5 to 14 inclusive and 51 of the Ellis Patent 1,197,276, and the description in said patent relating thereto for a detailed disclosure of numeral keys and their latches and manner of operation for those parts of the numeral keyboard and its accessories which are not shown in detail in the accompanying drawings.

Reference is to be made to the disclosures of the Ellis Patent 1,203,863, for the details of the construction and mode of operation of the accumulator, and to my Patent No. 1,508,267, more particularly to Figs. 1, 8, 9, 10, 11, 12, and 13 for a complete disclosure of the overdraft mechanism which is automatically operated by the accumulator when an overdraft occurs.

The mechanisms shown and described in these patents and, more particularly, the mechanisms heretofore specifically identified by the reference to the views or figures thereof afford a clear understanding of how the present improvements for locking the numeral keys may be operated when an overdraft occurs and released by the operator after they have been locked.

Referring to Fig. 14, the machine has a rack R^{50} for each bank or row of numeral keys, mounted to slide on two slotted cross bars K^3 and R^{92} . The movement of each rack R^{50} backward and forward is limited for the purpose of addition and subtraction by the stops K^{23} secured to the vertical sliding key stems of the keys, K^{51} , K^{52} , K^{53} , etc., to K^{59} . The key, K^{59} does not limit the travel of the rack, but permits it to go its full stroke which is limited by the downward projections at the ends of that part of R^{50} which slides in the groove in the bar K^3 . These stops, K^{23} are so arranged that they engage steps on the upper edge of the rack R^{50} and these steps and the stops, K^{23} are arranged vernier fashion so that from the first step to the first stop, K^{23} on the key stem K^{51} , the rack R^{50} could move a distance of one tooth, while stop K^{23} on the second key K^{52} would permit the rack R^{50} to move a distance of two teeth and the stop K^{23} on the key stem of K^{53} would permit the rack to move a distance of three teeth, etc., up to K^{59} , which serves the purpose of unlocking the rack R^{50} , by releasing the rack lock 68^k , and permitting the rack, R^{50} to move its full travel or nine teeth.

The rack R^{50} is moved in a rearward direction by means of the springs, R^{80} which are connected at their rear ends to a bar, R^{51} , extending between the side members of a bail, 45^R , which bail is secured to the shaft R^1 , and rotates with it. Mounted on the shaft R^1 , are a series of bell cranks, R^{45} , having three projecting arms, one projecting forward for the purpose of operating the 0 printing triggers, P^{57} , the other arm extending rearwardly for the purpose of connecting to the link P^{53} which serves to rotate the type sector P^{54} and if the bell crank, R^{45} is rotated about the shaft R^1 , the connecting link P^{53} will cause the type sector P^{54} to rotate about its center and bring the desired type to the printing line. The third arm from the bell crank, R^{45} extends in a downward direction and carries a pin R^{14} which engages a vertical slot in the lower side of the rack, R^{50} so that when the rack R^{50} moves forward and backward it communicates this motion to the bell crank R^{45} through the pin R^{14} and when the bail 45^R is moved to rotate toward the rear or right, in Fig. 14, the spring R^{80} which connects the bar R^{51} and the bell crank R^{45} , tends to move the rack R^{50} in a rearward direction.

until this travel is checked by one of the stops K²³ or some other obstruction to its movement.

The segmental rack, R⁵², mounted on the lower extending arm of the bell crank, R⁴⁶ is for the purpose of obtaining forced alinement of the type on the sector P⁶⁴ and this alinement segment R⁵² is secured firmly to the lower arm of the bell crank R⁴⁶. The alinement of the type through the segment R⁵² is brought about through the insertion of the blade R⁵³ mounted on the forward side of the alining frame R⁴⁴ which in turn is mounted upon the shaft R².

The handle, or the motor drive of the machine is adapted to cause rotation of shafts O1, R1 and R2, as explained in Ellis No. 1,203,863.

Referring to Figs. 11, 12, 13, underneath the keyboard K50, there is arranged a series of vertical plates 60K, which are called order plates. These are secured to the plates K50, by means of two rods K2, that pass through all of the order plates 60K, and the rods are held to the plate K50, by means of screws K18. The keystems K51, to K59, pass down on the left-hand side of the order plates 60K, and are held in contact therewith by means of hexagon-headed rivets K23, which pass through vertical slots in the plate 60K. These rivets K23, form the stops for the rack R50, and serve as a means of guiding the keystems K51, to K59, in a vertical direction. Above the rivet K23, opposite each of the keystems K51, to K59, there is an irregular shaped hole in the order plate 60K. Through the upper end of this hole, there is inserted a flat washer 59K, which has a rectangular slot through it, through which the keystem passes. This washer 59K, is held fixedly in the order plate 60K, and just below it there is a loose washer K99, of felt, mounted on the keystem, and below this felt washer K99, is a third washer 56K, which is secured to the keystem and moves with it. Between the washer 56K, and the bottom of the hole aforesaid, is a compression-coil spring K80, the lower end of which rests against the edge of the hole in the order plate 60K, and the upper end presses against the washer 56K, mounted on the keystem. When a keystem is depressed, it carries down with it the washer K99, and compresses the spring K80, and when the keystem is released, the spring K80, returns it to its normal position. The order plates 60K are further maintained in position by two bars extending horizontally across their front and rear edges, which bars are marked 61K, and 62K. These bars are notched in a suitable fashion to engage each of the order plates 60K, and are held in position by means of a small clamp nut K33, and a screw K18, passing through the bars 61K, and 62K. The lower

side of the order plate 60K, rests in small slots in the cross bar K3, extending between the side frames of the machine. The cross bars 61K, and 62K, serve also as a means of supporting the pivots K1, of the latches 52K, which hold the keystems K51, to K59, in their depressed position during the operation of the machine. These latches are arranged so that there is one to each column of nine keystems, and they swing sidewise from the keystems. Swinging about the same pivot K1, are the keystem locks 53K. There is also mounted on the pivot shaft K1, the rack lock 68K, and suitable springs K82, control the keystem latch 52K, and lock 53K, and a spring K83, controls the rack lock 68K. The locks 53K, are each provided in their rear ends with a hook 54K and a cross bar 65K, is supported by and engages each of these locks 53K.

The shiftable bar 65K is provided with a series of notches A adapted to co-operate with the lock latches 53K in a manner which is clearly shown in Figs. 11 and 12.

The operation of the keystem, its latch 52K, its lock 53K and the rack lock 68K is set forth in detail in Ellis Patent No. 1,197,276.

In Figures 1, 3, and 14, the shaft O1 is shown in normal position, the position appearing in Fig. 3 of patent 1,197,276 and Fig. 2 of Patent 1,203,863. In that position, the abutment of the restoring pin 2 against the roller 3 of the crank lever 63K causes the shiftable bar 65K to be moved toward the right, Fig. 1. It will be understood that Fig. 1 is a view looking toward the rear of the numeral key latching means, corresponding to Fig. 12 which is taken from the Ellis Patent No. 1,197,276, with the addition of the improved cam lever 63K, 163K.

The holding of the parts in the position shown in Figs. 1 and 3 permits the lock latch 4, under the tension of spring 4^a, to enter the notch X which is provided in the extreme end of the bar 65K.

The frame piece appears at 62K, other pieces of the supporting frame being omitted for the sake of clearness.

Normally, the lock latches 53K are held out of the downward path of travel of the studs K25 by the action of the notches A.

When the machine is operated, the shaft O1 swings the restoring pin 2 from the position of Figs. 1 and 3 to that of Figs. 2 and 4. Figs. 2 and 4 represent the extreme extent of turning of the shaft O1 and the actions of the parts when moving from the normal position of Figs. 1 and 3.

The arm 50^a which is secured to shaft O1 is utilized for the purpose of actuating the latch 4. To that end there is carried by the arm an adjustable eccentric roller O30 which is adapted to wipe against the latch 4 to shift the latch from the locking position of

Figs. 1 and 3 to the unlocking position of Figs. 2 and 4 when the shaft O¹ is turned from normal position to the position appearing in Fig. 4. The first approximate ten degrees of the movement of the shaft O¹ brings about a movement of the key latches 53K to the position shown in Fig. 2, thereby preventing the key stems K51 from being depressed.

10 Illustration is given only in Figs. 1 and 2 of two orders of key stems, the others being omitted for the sake of clearness, as they appear in Figs. 11 and 12.

In Fig. 2 the right-hand key stem K51 is held in its depressed position by its latch plate 52K. Both of the lock-latches 53K have moved in a counterclock-wise direction, allowing the bent parts of the latches to rest against the sides of the key stems.

20 By reason of the latching action, it will be obvious that no stem which has not already been depressed can be depressed once the bar 65K has been shifted to the position shown in Fig. 2 because the lateral parts of 25 the key latches will lie directly under the studs or lugs K25 of those key stems which have not been depressed.

The various shutter latches 53K for the banks of numeral keys are operated by the 30 release bar 66K, Figs. 11, 12, 16 which engages a bell crank lever L⁵³, which in turn is operated by a sliding bar L⁵¹ extending forwardly and rearwardly of the machine, Figs. 11, 15, 16. In addition the numeral

35 keys are released on the return stroke of the shaft O¹. Referring to Fig. 15, a plate D⁵⁵ is carried by O¹ and on said plate is a roller D³⁰. As the shaft O¹ is turned in its forward direction the roller D³⁰ moves to the

40 right which permits the hook L⁶³ to engage the roller D³⁰. On the return stroke of the handle O⁵⁸ and the shaft O¹, the roller D³⁰ engaging the hook L⁶³ which is pivoted on the sliding bar L⁵¹, draws the sliding bar

45 L⁵¹ toward the rear of the machine and so operates the crank L⁵³ and the transverse bar 66^K releasing the numeral keys. The upward extending arm of the hook L⁶³ engages a stud L³⁵ at a suitable time to re-

50 lease the hook L⁶³ from the roller D³⁰ and permits the sliding bar L⁵¹ and its connections to the transverse sliding bar 66^K to resume their normal position. In the event

55 of an overdraft, the keys which have been depressed are released from the latch 52K at C (Fig. 2) when the machine is put through its cycle of operations, but these keys are prevented from rising by the engagement of latch 53K with stud K25, as shown in said figure and thus remain in operative position.

The release of the numeral keys when subtraction takes place is done in the same time and by the same mechanism that releases the numeral keys in addition.

When a total or sub-total is to be taken it is necessary to release the numeral keys during the first fifteen degrees of the forward stroke of the handle O⁵⁸ and this is accomplished in the following manner. The total and sub-total keys K⁶⁴ abut at their lower end against a diagonally sliding piece L⁵² which sliding piece has a turned over lip near its rear upper edge which engages a stud L¹¹ on the lower edge of the irregular shaped piece L⁶¹. This piece L⁶¹ is pivoted to the lower end of the latch L⁵⁵ for the repeat key K⁶² and is held in its upper position by a suitable spring. A second stud L¹⁰ in the lower edge of the piece L⁶¹ comes underneath a second hook L⁶⁴ pivoted on a downward extension from the piece L⁶¹, and the hook L⁶⁴ and the hook L⁶³ are connected together by a suitable spring, tending to raise the hook L⁶⁴ and move the hook L⁶³ downward. The tension of the spring holding the piece L⁶¹ in its upward position is strong enough, however, to cause these different parts to normally assume the position shown in Fig. 15. When, however, a total or sub-total key, as K⁶⁴, is depressed it depresses the piece L⁶¹ and carries down the piece L⁶¹ which permits the spring to raise the hook L⁶⁴ until it comes into engagement with a roller D³¹ on the lower end of a pivoted cam D⁶³ and this cam D⁶³ is in contact with a roller D³² mounted on the plate D⁵⁵ secured to the shaft O¹.

When the parts have been thus arranged, the initial movement of shaft O¹ will cause roller D³² to swing the cam D⁶³ to the left and so move the hook L⁶⁴ and the piece L⁶¹ to the left, thereby releasing the numeral keys. Reference is to be had to Ellis Patent No. 1,203,863 for a more detailed disclosure of these parts and their operation.

Assuming that the machine on which the present improvements are used is provided with the overdraft automatic locking mechanism set forth in my Patent No. 1,508,267, the action of said overdraft locking mechanism will be clear by reference to Patent No. 1,508,267, particularly to Figs. 8, 9, 10, 11, 12, and 13 thereof, and to Figs. 17, 18, 19 and 20 hereof.

For the purpose of locking the bar 65K in position where the lock-latches 53K will prevent the key stems K51 from being depressed as shown, for instance, in Figs. 2, 8 and 10, there is provided a locking trigger 10 which is pivotally mounted in any suitable manner as, for instance, at 10' on a part of a frame F. This trigger is normally in the position shown in Fig. 9 but when the overdraft mechanism of the accumulator comes into action on the occurrence of an overdraft in the machine, the bar or link 69L is shifted in the direction of the arrow, Fig. 9, which

brings about a position of the trigger 10 as shown in Figs. 8 and 10, whereupon the trigger is disposed so that its bent end constitutes a stop or abutment for the end of the shiftable bar 65K and prevents said bar from returning to the normal position shown in Fig. 1 and locks it in the position shown in Fig. 2 where it is impossible for the latch 4 to enter the slot X. When the bar 65K is in this blocked position, the key stem latches 53K are held so that the key stems are locked against depression and hence the operator is given a signal that there is an overdraft in the accumulator.

To take care of this condition, there is provided a secondary or safety pawl 163K which is pivoted at 13 to the lever 63K and is connected to it by a spring 15. The lever 63K and the pawl 163K collectively co-operate with a pin 14 carried by the bar 65K. The spring 15 normally enables the parts 63K and 163K to swing as a unit on the pivot 14^a but this spring permits yielding as shown in Fig. 8 when the shifting of the bar 65K is blocked by the trigger 10, so that there will be no breakage or interference when the rock shaft O1 turns while the trigger 10 is blocking the bar 65K.

The crank lever and safety pawl appear in detail in Fig. 5, and the trigger is shown in detail in Fig. 5A.

To restore the trigger 10 to normal position and to maintain it normally in the position shown in Fig. 9, there is provided a spring 10^a.

Normally the parts are in the position shown in Figs. 1 and 3 and the key stems K51 may be depressed in the different banks of the keyboard and the machine operated in the usual manner as will be clear from the Ellis Patents 1,197,276 and 1,203,863 and the foregoing disclosure.

The adding and subtracting accumulators of Ellis Patent No. 1,203,863 appear in Fig. 14 and the overdraft mechanism therefor is shown in Figs. 18, 19, 20 in accordance with my Patent No. 1,508,267. The keys and means setting the respective accumulators for subtraction and for the taking of totals and sub-totals are shown in Fig. 17.

Reference is to be had to Patents 1,203,863 and 1,508,267 for a full disclosure of the accumulators and the manner in which they may be conditioned for addition, subtraction or the taking of a total or sub-total, and their co-operation with the racks R50, the parts and mechanisms being numbered to correspond with similar parts and mechanisms in said patents.

Particular description, however, will now be given of the overdraft mechanism of my Patent No. 1,508,267 in order that the relationship of the present improved numeral key locking mechanism thereto will be clear.

Referring first to Figs. 19 and 20, the

former shows the shift bar N90 set to cause the accumulator for carrying on a subtracting operation before an overdraft has taken place, whereas Fig. 20 shows the position of the parts of the overdraft mechanism after an overdraft has occurred.

When an adding operation is desired, the shift bar N90 is set as shown in Fig. 14, upper accumulator.

When the subtracting key K67, is depressed as shown in Fig. 17, the shift bar N90 is turned to the position shown in Fig. 19 to block the adding cam hook N55 and free the subtracting cam hook N56 for use. A link 64L, Fig. 17, which is shifted when subtracting key K67 is depressed as in said figure, effects this setting of the shift bar N90.

Referring now to Figs. 18, 19, 20.

Pivoted to the order plate 53N of the highest order by a stud N16, is an overdraft lock latch 66N. A spring 81N which co-operates with the overdraft lock latch 66N and the order plate 53N, tends to swing the overdraft lock latch so that its point X' will move in a clockwise direction. This movement is prevented when the shift bar N90 is set for addition as shown in Fig. 14, there being a rounded projection X'' on the overdraft lock latch which is pressed downwardly by the shift bar N90 when the latter is set for addition. Consequently when the accumulator is set for addition as shown in Fig. 14, the pointed end X' performs no function.

However, when the shift bar N90 is set for subtraction, as will be the case when the subtracting key K67 is depressed and the machine operated, the turning of the shift bar N90 from the position shown in Fig. 14 to the position shown in Fig. 19, relieves the pressure against the projection X'' and thereupon the spring 81N turns the overdraft lock latch 66N so that the point X' comes against the rear end of the subtracting pawl or hook N62 which arrests it as shown in Fig. 19. The turning of the wheel N50 of the highest order either directly by rack R50 or by carrying, resulting in an accumulation of subtracted items, causes the cam N56 to engage the tip of the subtracting pawl or hook N62 by moving from the position shown in Fig. 19 to that shown in Fig. 20, thus depressing the left hand end of the subtracting pawl and elevating the right hand end thereof. This action results in the release of point X' so that the spring 81N immediately swings the overdraft lock latch to the position shown in Fig. 20 whereupon it engages the rear end of the subtracting pawl or hook N62 and holds it in that position until released as hereinafter described.

To prevent the "balance" or total key K63 for the upper accumulator and the sub-total or total deposits key K64 from being oper-

ated when the upper accumulator represents an overdrafted condition, means are provided for automatically locking these keys when this condition prevails, said means being operated from the overdraft shaft N6.

Referring to Figs. 17, 18, there is provided on the left hand end of the shaft N6 a crank N68^b. Pivoted on the screws L19L of the latches 56L and L56 for the keys K64 and K63, are locks 67L and 68L whose lower ends are positioned so that they can be engaged with notches 167L in the stems of keys K63, K64, when said keys are in elevated or normal position. For the purpose of causing the locks 67L, 68L, to engage the notches 167L or to be released therefrom by the turning of overdraft shaft N6, there is provided an operative connection comprising a link 69L pivoted to the crank N68^b 15 and a link or slide bar 66L pivotally connected to link 69L at L24L. The link 66L is pivoted to studs L18L on the upper ends of the locks 67L, 68L. Near the rear end of the slide bar 66L there is a slotted part 66L^a 20 which slides on a pin or stud L20L on the side frame of the machine, thereby guiding and suspending the bar 66L. Normally the crank N68^b is in the position shown in Figs. 17 and 18 even when the subtracting key K67 25 is depressed.

When an overdraft condition exists in the upper accumulator which causes the overdraft latch 66N to move to the position shown in Fig. 19, the rocking of the shaft N6 turns the crank N68^b backwardly and thereupon the locks 67L, 68L, are swung so that their lower ends engage the notches 167L. This results in locking the keys K63 and K64 so that the operator cannot take a 30 total or sub-total and a signal is thus given, indicating to the operator that the account is overdrawn and necessitating the manual operation of the decimal slide P67 or such other means as may be employed to unlock 35 the keys K63, K64.

To release the total and sub-total keys, the hand-operated "decimal slide" P67 or some other suitable means is provided, said device being adapted, when operated, to shift 40 the link 73P, thereby to rock the crank E60 carried by shaft I1 which rocks the arm C which, in turn, rocks crank N68^b, shifting the link 69L which releases the latches 67L and 68L from the total and sub-total keys 45 K63, K64.

When an overdraft has taken place in the accumulator, the action of the overdraft mechanism, which will be clear from the foregoing description and the disclosures of 50 my Patent 1,508,267, causes the shifting of the link 69L from the position shown in Fig. 9 to that shown in Figs. 8 and 10, positioning the trigger 10 in the extreme forward position appearing in Figs. 7 and 10. 55 While the O1 shaft returns to normal posi-

tion, the locking trigger 10 remains in the position shown in Figs. 8 and 10 where it is directly in the path of the bar 65K and prevents said bar from returning to normal position. The pressure of the pin 2 against 70 the roller 3, as the shaft O1 returns to normal position forces the lever 63K to the position shown but as the spring 15 yields and as there is no positive connection between the lever 63K and the pin 14, there is no 75 interference with the locking action of the locking trigger 10 and the retention of the lock-latches 53K in the locked position shown in Fig. 2.

Finding that the numeral keys cannot be 80 depressed, the operator thereby is given a signal which indicates to him that an overdraft exists in the accumulator.

By referring to my Patent No. 1,508,267 85 issued September 9, 1924 on overdraft key locking and indicating mechanism on page 9, beginning on line 28, I mention that when an overdraft has taken place no further addition should be permitted in the accumulator. In the mechanism of Patent No. 1,508,267, in 90 order to prevent further addition after an overdraft has taken place, a hook 69L^a is arranged on the link 69L, that embraces the stud D-21 and renders the credit accumulator inoperative insofar as addition is 95 concerned.

With the overdraft key lock mechanism as set forth in my Patent No. 1,508,267, it is desirable to prevent further addition after an 100 overdraft has taken place. On the contrary, with the mechanism of my present application for overdraft key locking mechanism it is not desirable to prevent addition after an overdraft has taken place. Therefore the hook 69L^a on the link 69L of my Patent No. 1,508,267 is omitted, thus permitting the accumulator to go through its operation as of addition, but as the numeral keys are locked against their depression no addition is actually performed.

As set forth heretofore, in connection with my present improvements, when an overdraft has taken place in the accumulator, the operator's attention is called to this condition by the inability to depress any of the 110 numeral keys, either for the purpose of addition or subtraction. The adding key that controls the addition for the credit accumulator is now depressed by the operator and the machine is operated, thereby adding back the exact amount which has caused the 115 overdraft.

Should the mechanism be provided with a key to manually release the depressed numeral keys, the credit accumulator will go 120 falsely through its cycle of addition.

It is to be understood that when the credit 125 accumulator is set for addition, the shift bar N-90 is set as shown in Fig. 9 of my Patent, No. 1,508,267, the abutment of the 130

shift bar N-90 against the overdraft lock latch 66-N causing the extreme lower end X-1 of the said lock latch 66-N to be held away from the backward side of the subtracting pawl N-62.

When the accumulator is set to perform subtraction, the shift bar N-90 has been caused to move to assume the position shown in Fig. 19 hereof, thus allowing the overdraft lock latch to stop against the subtracting pawl. Inasmuch as the overdraft lock latch 66N is under the tension of the spring 81-N as explained in my said patent, said overdraft lock latch 66-N assumes the position shown in Fig. 20 hereof after an overdraft has taken place, and through its train of mechanism causes the balance key or keys to become locked. However, in the present application I prefer to use this same initial movement of the lock latch 66-N to lock the numeral keys as hereinbefore explained. When the shift bar N-90 is moved to the subtracting position as shown in Fig. 19 hereof, it is latched in this position by the latch 70-N illustrated in Figs. 3 and 5 of my Patent No. 1,471,770, October 23, 1923.

Assuming that an overdraft has taken place and the operator's attention is called to this fact by being unable to continue with addition or subtraction of items, for the reason that the numeral keys are locked against depression, the credit-add key is depressed and the machine is operated. While the machine is going through its cycle the latch 70-N is released from the path of the shift bar N-90 by the restoring bar N-49 (Fig. 2, Patent No. 1,471,770) and the shift bar is permitted to assume its normal position as shown in Fig. 14 hereof. The shift bar N-90 forms an abutment against the overdraft lock latch 66-N and causes the trigger 10 of the present application to assume its normal position as shown in Figs. 7 and 9, thereby removing the lock-latch 45 from the path of the lock stud K-25 in the numeral key stem K-51.

What I claim is:

1. In a calculating machine, the combination with an accumulator adapted for either addition or subtraction, of settable numeral keys on which the numbers or amounts which are to be added into, or subtracted from, the accumulator may be manually set up, means adapted to automatically locking the numeral keys which remain undepressed to prevent them from being operated to set up a number after an "overdraft" has occurred in the accumulator, and means for releasing said locking means.

2. In a calculating machine, the combination with an accumulator adapted for either addition or subtraction, of settable numeral keys on which the numbers or amounts which are to be added into, or subtracted from, the accumulator may be manually set up, means

operated by the accumulator adapted to automatically effect locking of the numeral keys which remain undepressed to prevent them from being operated to set up a number after an "overdraft" has occurred in the accumulator, and means for releasing said locking means.

3. In a calculating machine, the combination with an accumulator adapted for either addition or subtraction, of numeral keys on which the figures or amounts to be added into, or subtracted out of, the accumulator may be manually set up, locking means which, in the normal use of the numeral keys, retain the keys in set position after said numeral keys have been manually set to enable the amounts or figures represented thereby to be entered into said accumulator, and overdraft mechanism automatically operated when an "overdraft" occurs in the accumulator, said overdraft mechanism being adapted, when thus automatically operated, to interfere with the normal action of the locking means aforesaid, thereby to prevent such numeral keys as have been set from being automatically restored and those numeral keys which have not been set from being manually operated.

4. In a calculating machine, the combination with the numeral keys thereof on which numbers or amounts may be manually set up, of latches for holding the numeral keys in set position when said keys have been manually set, means normally operated when the machine is going through its cycle of operations adapted to automatically release the aforesaid latches so that the numeral keys will be freed for subsequent use, an accumulator adapted for either addition or subtraction, overdraft mechanism adapted for automatic operation by said accumulator when an overdraft occurs, and means operated by said overdraft mechanism adapted for interfering with the normal operation of the latches, thereby to prevent such numeral keys as have been set from being automatically restored and those numeral keys which have not been set from being manually operated, without interfering with an idle operation of the machine.

5. In a calculating machine, the combination with the numeral keys thereof, of latches for holding the numeral keys in set position when said keys have been set, means operated when the machine is going through its cycle of operations adapted to release the aforesaid latches, an accumulator, overdraft mechanism operated by said accumulator, a shiftable bar which determines whether the latches shall be arranged to permit depression of the numeral keys, or, to prevent depression of said keys, and a locking trigger which is set by the action of the overdraft mechanism to lock said bar

and maintain the latches in their latched position when an "ovedraft" occurs in the accumulator, thereby to prevent depression of any numeral keys which have not been set.

5 In testimony whereof I affix my signature.

FREDERICK W. BERNAU.
